FILLING AND SEALING DEVICE FOR CONTAINERS

Frank Brodsky, New York, N. Y.

Application August 12, 1938, Serial No. 224,447

4 Claims. (Cl. 226—79)

This invention relates to filling devices for small containers, particularly jars or pitchers for cream, syrup and the like, and has for its main object to provide such a device which will be efficient and practically automatic in its operation.

Another object of this invention is to provide a device of the character mentioned, which will be adapted to fill a great many of such small containers, pitchers, jars and the like simultaneously removing the row when filled and replacing it by a new row of such containers easily and quickly.

Still a further object of my invention is to provide a filling device for a plurality of such small containers which will be safe against waste of spilling of the material to be filled, which will be secured against over or under filling of the containers or any of them, and which will also seal the containers when filled to the desired degree.

Still a further object of my invention is to provide a device as characterized hereinbefore which will be simple and still, so to say, fool-proof in operation, which will be reliable, and inexpensive to manufacture, and in which the removal of a filled row of containers, the replacing of the same by a new empty row of them, the filling of a new row, the sealing and again their removal and so on will be done in succession in a semi-automatic manner by the device itself.

Still further objects of this invention will be apparent as the specification of the same proceeds.

35 In the drawings forming a part of this specification and accompanying the same:

Fig. 1 is a plan view of my device, the upper part of the front portion of the same having been removed;

40 Fig. 2 is a longitudinal sectional elevation of my assembled machine, the section being taken on the line 2—2 of Fig. 1;

Fig. 3 is another sectional elevation of my device, generally on the line 3—3 of Fig. 1;

45 Fig. 4 is a horizontal elevation of my device, the section being taken on the line 4—4 of Fig. 2;

Fig. 5 is a detailed view, showing a sliding plate used in my device to propel the sealing disks over and on the filled containers;

50 Fig. 6 is a fragmentary detail, showing the storage stack of the sealing disks with their said propelling sliding plate, and

Fig. 7 is another sectional fragmentary detail, showing a portion of the filling mechanism

55 Referring now to the drawings more in detail, by characters of reference, the numeral 10 indicates the main plate or table of my device, standing on two side leg plates 11 and 12 thereunder. Two upper side plates 13 and 14 are secured to the table plate 10, forming a U-shaped upwardly open structure in which is housed most of the operation parts of my device. A stationary cover plate 15 is secured over the table plate 10, spaced apart therefrom, leaving sufficient room for a sliding plate 16 between the two. A generally rectangularly shaped cross bar 17 is arranged over the table plate 10 in the front part thereof, resting on two coiled springs 18 and 19 which have the tendency to push said cross bar 17 in an upward direction, said bar being slidably arranged on pins 20 and 21.

20 A plurality of filling funnels 22 are secured, preferably in an evenly spaced apart manner in the cross bar 17, each having an upwardly widening upper funnel 23, a central tube portion 24 and a lower downwardly widening funnel 25 with a cylindrical termination 26. A hole 27 is provided in the table plate 10 under each cylinder 26, said cylinder being adapted to snugly but 25 slidably pass through the respective hole 27, while the upper cover plate 15 is shorter than the table plate 10 so as to leave the hole 27 free and uncovered.

20 A rectangular hollow body or filling container proper 28 is arranged across my device secured into the upper side plates 13 and 14, being axially aligned with the filling funnels 22 and having a small filling hole or aperture 29 in its bottom corresponding to the center line of each filling funnel 22. A general reservoir 30 is arranged over said filling container 28, communicating therewith through the pipe connection 31. A longitudinal bar or plate 32 is arranged within the closed filling container proper 28, being upwardly and downwardly slidable therein and having a small downward closing pin or needle 33 for each opening 29, and an upward center rubber disk 34 for closing or opening the communicating pipe 31 between the filling container proper 28 and the reservoir 30. Two pipes 32a and 33a are arranged at the two sides of the filling container 28, communicating with the inside thereof, and two rods or pins 35 are slidably arranged in said pipes, their lower ends being secured into the longitudinal bar 32, as at 35a. A small transverse cross bar 36 is secured to the upper end of each pin or rod 35 and a downward rod 37 is secured to the outer free end of each cross bar 36. 30 and 35 and 36 and 37

A longitudinal frame member or plate 38 is secured to the lower ends of the downward bars 37, said plate 38 slidably engaging the inner wall 39 of the rectangular filling container proper 28. At two places, the sliding plate 38 is downwardly extended and inwardly projecting to form two fingers or arms 40, and a coiled spring 41 is placed between each arm or finger 40 and the bottom 42 of the filling container 28. Between two lugs 43 and 44, secured on the cover plate 15 in the center line thereof, is a plate lever generally indicated by the numeral 45, rockable on a pivot 46 and carrying the handle 47 by which it may be manipulated. A slot 48 is provided in the cover plate 15, permitting the outer circumferential portion of the plate lever 45 to enter and slidably move in said slot, and the sliding plate 16, under said cover plate 15, has a plurality of apertures 49 arranged in alignment with said slot 48, and teeth 50 arranged on a portion of the circumference of the rockable plate lever 45 may engage said apertures and move said plate 16 in either direction between the plates 10 and 15, as will be explained hereinafter. (Stroke and directions indicated at 18a, Fig. 6.)

Also rockable between the lugs 43 and 44, as around the pivot 51, is the lever 52, having the inner branch 53 adapted to be engaged with the various cam surfaces on the plate lever 45, and the outer branch 54, reaching underneath the sliding plate 38, and the filling container 28, and over the cross bar 17. Two supporting and guide rails 55 and 56 (Figs. 2 and 3) are secured to the inner sides of the lower or leg plates 11 and 12, and a plate 57 is slidably resting on them between said two leg plates. Longitudinal walls 58, and transverse walls 59 are built on said plate 57, providing a receiving frame with compartments 60 for receiving rows of small containers or pitchers 61, as will be understood. Outside of said compartments on the two longitudinal marginal edges of the plate 57, equidistantly spaced, teeth 62 are provided in the surface of the plate and another row of equidistantly placed slots 63 are cut into the respective edges of the plate 57.

On the inner side of each of the leg plates 11 and 12 is arranged a link mechanism, generally indicated by the numeral 64, consisting of a lever 65 rockable on the pivot 66, the lower end 67 of which is pivotally connected to a propelling finger or arm 68, while the upper end 69 thereof is pivotally connected to a link member 70, the forward end 71 of which is again pivoted on a small plate 72, depending from the respective side of the sliding center plate 16, the main or table plate 10 having a slot provided therein (not shown) adjacent to each leg plate 11 and 12 to permit a backward and forward moving of the depending plate 72.

The use and operation of my device is as follows:

The compartments 60 on the sliding plate 57 will be filled with the pitchers or containers 61 and then placed over the rails 55 and 56 and pushed forwardly in the device until the first row of said containers, generally indicated by the numeral 74, is set in alignment with the filling tubes and funnels 22, as shown in Fig. 3.

Normally, the springs 41 will press the sliding plate 38 downwardly by acting on its forwardly projecting fingers or extensions 40. The plate 38 will carry downwardly the two upward bars 37, the cross bars 36 and the pins or rods 35,

and the longitudinal bar 32 in the container 28 will be placed downwardly closing the exit or filling openings 29, in its bottom, through the closure pins 33 and opening the connection 31 to the reservoir 30. This is the normal state of said parts of my device, so that, normally, the filling container 28 is open to the reservoir 30 and will be filled with the contents 75 of said reservoir, like cream, syrup, etc., while the exit openings 29 of the filling container 28 are normally closed preventing the escape of any material therefrom.

When it is desired to fill the said first row 74 of containers in my device, the handle 47 will be turned upwardly, as shown by the arrow 77, to its uppermost positions, as indicated in an imaginary fragmentary manner at 47a by the dot and dash lines in Fig. 3, in which position the upper cam portion 78 of the rocking plate lever 45 will engage the left-hand end 53 of the rocking lever 52 and will press it downwardly, as indicated by the arrow 79, and causing the branch 54 of said lever to move upwardly, as indicated by the arrow 80, engaging and moving the plate 38 in an upward direction. Such a movement of the plate 38 will carry all the devices secured to said plate in an upward direction in a similar manner as has been described in connection with the movement of said plate 38 in a downward direction, ultimately moving the closure pins 33 upwardly out of the filling openings 29 and, at the same time, closing the exit 31 from the reservoir by the disk valve 34.

The contents of the filling container 28 is now permitted to flow out through the openings 29 through the intermediate filling funnels and tubes 22 into the containers 61, and said container 28 is designed in such a way that its contents will be exactly sufficient to fill each container 61 to the desired degree.

After the container 28 has been emptied of all the liquid and all the pitchers 61 have been filled, the operating handle 47 of my device will be turned in a reverse direction, backwardly or downwardly, as indicated by the arrow 81, and its cam 78 will release the branch 53 of the rocking lever 52, whereupon the branch 54 of said rocking lever will at once be moved downwardly in the reverse direction to arrow 80, permitting the springs 41 to act to move the plate 38 and its associate parts downwardly, returning the longitudinal bar 32 in the container 28 into its said normal position, sealing the exit openings 29 by the pins 33, and permitting the reservoir 30 to refill said container 28, as will be understood.

On the further rotation of the handle 47 and plate lever 45 in the direction of the arrows 81, the teeth 50 will engage the apertures 49 and will move the plate 16 in a forward direction, indicated by the arrow 82, in Fig. 5. An appropriate sealing disk 83 has been placed into each semi-circular front recess 84 of the plate 16 over the table plate 10 by a device and in a manner to be described presently, and on the forward movement of the plate 16 in the direction of arrow 82, each disk 83 will be dropped over a respective container 61 through the respective opening 27 in the plate 10, as will be understood. A further movement of the plate lever 45 in the direction of arrow 81, that is, a further pressing of the handle 47 in a rearward direction, will move the teeth 50 out of engagement with the plate 16 and will place a second cam portion 85 of the plate lever 45 into engagement with the end 53 of the rock-

ing lever 52, as indicated in Fig. 3, and upon the further pressing of the handle 47 and rocking of the plate lever 45 in the direction of arrow 81, said cam 85 will lift or raise the lever end 53 upwardly, opposite to the direction of arrow 79, and will move the lever end 54 downwardly, opposite to the arrow 80, said lever end 54 now engaging the cross bar 17 and pressing it downwardly, against the action of the springs 18 and 19, the lower cylindrical ends of the filling funnels 22 entering the upper openings of the pitchers or containers 61 and sealingly pressing the respective disks 83 thereinto. In this manner, the first row of the containers 61 has been filled and sealed, and my device is ready to fill and seal the second row thereof. For this operation, lever 47 will again be pushed into its uppermost position 47a and the operations described hereinbefore repeated.

It will be noted that upon the upward movement of the handle 47 in the direction 17 from the position indicated in Fig. 3, after sealing the first row 74 of the filled containers, teeth 50 will engage the plate 16 and move the same rearwardly, opposite to the direction indicated by the arrow 82. This movement of said plate will rock the link mechanisms 64 on the two side leg plates 11 and 12 into the positions indicated by dotted lines in Fig. 3, and the forward catch or dog end 86 of the finger or bar 68 will engage the first tooth or slot 62 in the plate 51 and will move said plate with the compartments thereon in a forward direction until the first row 74 of the containers 60 has been forwardly removed from my device and the second row 74a placed into its earlier positions underneath the filling funnels 22, so that upon the further operation of the arm 47 in an upward direction, the second row 74a of the container 61 will be filled, as has been described hereinbefore with reference to the first row 74 thereof. Corresponding to the apertures 27 and the recesses 84 in the respective plates 10 and 16, apertures 87 are provided in the cover plate 15 to the rear of said apertures 27 (Figs. 1 and 6).

A cylindrical backwardly inclined filling guide 88 may be provided over every opening or hole 87 containing a stack of sealing disks 83, and it will be obvious that upon the forward movement of the plate 16, each recess 84 will carry the lowermost sealing disk 83 from its stack, while upon the rearward movement of said plate 16, its recesses 84 will again be filled with the next lowermost disks in the stacks 84.

It also will be seen that upon the forward movement of said plate 16, that is preparatory to the sealing operation and the position of the parts shown in Fig. 3, the link mechanism 64 will be operated in a reverse direction to the one described hereinbefore, and placed into its position shown by the full lines in Fig. 3, the catch or dog 86 riding rearwardly, leaving the first notch or tooth 62 and riding idly until it will arrive and snap into the next notch 62, in this manner being ready to again propel the plate 51 with the pitchers 61 thereon with another row when the handle 47 is again moved upwardly preparatory to the filling operation, and the teeth 50 will again move the plate 16 in a rearward direction.

I may, finally, also provide a yieldable resilient locking device 88a at each side of my device, their outwardly bent portions 89 being adapted to snap into a respective slot 63 in the edge of the plate 51 and thereby secure an aligned position for the respective row of pictures 61 with the row of the

filling funnels 22, while on the forward movement of said plate 51 under the action of the arm or finger 68, said resilient locks will yield, moving outwardly from the slots 63 and permitting such a movement of the plate 51 with the containers 61 thereon.

What I claim as new is:

1. In a filling device for a plurality of containers, a filling container proper having an exit aperture for each container and a refilling opening, a movable member in said filling container, one extreme position of which is adapted to open said exit apertures and close said refill opening, the other extreme position of the same, vice versa, being adapted to close said exit apertures and open said filling opening, means to move said member in one or in the other extreme position, said means to move said member including spring means normally placing said member in a position closing said exit apertures, a rockable lever, and an operating lever actuated by said rockable lever in one or in the other direction, one position of said operating lever permitting the operation of said spring means, and the other position counter-acting the same and placing said moving member into its other extreme position, closing said refill opening and opening said exit apertures.

2. In a filling device for a plurality of containers, a filling container proper having an exit aperture for each container and a refilling opening, a movable member in said filling container, one extreme position of which is adapted to open said exit apertures and close said refill opening, the other extreme position of the same, vice versa, being adapted to close said exit apertures and open said filling opening, means to move said member in one or in the other extreme position, means to press a sealing disk on each container after the same has been filled, said pressing and sealing means normally being kept in an inoperative position, said means to place said member into one or the other of its extreme positions including spring means normally placing said member in a position closing said exit apertures, a rockable lever, and an operating lever actuated by said rockable lever in one or the other direction, in one position permitting the operating of said spring means to close said exit apertures, and in the other position counteracting the same and placing said movable member in its other extreme position, closing said refill opening, and in said first position said operating lever also acting on said means to press and seal said disks, while said exit openings are closed.

3. In a filling device for a plurality of containers, a filling container proper having an exit aperture for each container and a refilling opening, a movable member in said filling container, one extreme position of which is adapted to open said exit apertures and close said refill opening, the other extreme position of the same, vice versa, being adapted to close said exit apertures and open said filling opening, means to move said member in one or in the other extreme position, a slidable frame member for carrying rows of containers to be filled, one row at a time being adapted to be placed in aligned relation with said exit apertures, said means to move said closing member for said exit apertures and said refilling opening, respectively, also operating said sliding frame in such a manner that while said exit openings are closed, said frame will move to place the next empty row of containers to be filled in juxtaposition with said apertures.

4. In a filling device for a plurality of con-

tainers, a filling container proper having an exit aperture for each container and a refilling opening, a movable member in said filling container, one extreme position of which is adapted to open said exit apertures and close said refill opening, the other extreme position of the same, vice versa, being adapted to close said exit apertures and open said filling opening, means to move said member in one or the other extreme position, means to place a sealing disk on each container after the same has been filled, means to press and seal said disks in the openings of the respective containers to be filled, said sealing means normally being kept in an inoperative position, said means to place said member into one or the other of its extreme positions including spring means normally placing said member in a position closing said exit apertures, a rockable lever and an operating lever actuated by said rockable lever in one or the other direction, in one posi-

tion permitting the operating of said spring means to close said exit apertures, and in the other position counteracting the same and placing said movable member in its other extreme position, closing said refill opening, and in said first position said operating lever also acting on said means to seal said disks and causing said containers to be sealed by said disks, while said exit openings are closed; a slidable frame member carrying rows of containers to be filled, one row at a time being adapted to be placed in aligned relation with said exit apertures, said means to move said closing member for said exit apertures and said refilling opening, respectively, also operating said sliding frame in such a manner that while said exit openings are closed, said frame will move to place the next empty row of containers to be filled in juxtaposition with said apertures. 5 10 15

FRANK BRODSKY. 20
